Primary Examiner — Eric L Goodman*Assistant Examiner* — Sarah L Smith(74) *Attorney, Agent, or Firm* — Tarter Krinsky & Drogin LLP(57) **CLAIM**

The ornamental design for a flashlight with an electronic insect repellent, as shown and described.

DESCRIPTION

FIG. 1 is a perspective view of a flashlight with an electronic insect repellent;

FIG. 2 is a front view thereof;

FIG. 3 is a first side view thereof;

FIG. 4 is a rear view thereof;

FIG. 5 is a second side view thereof;

FIG. 6 is a bottom view thereof;

FIG. 7 is a top view thereof; and,

FIG. 8 is a perspective view of a lower portion covering an electronic insect repellent portion of the flashlight.

The broken lines shown in the figures show portions of the flashlight that form no part of the claimed design.
